UNITED STATES PATENT OFFICE.

ANGELO LATTANZI, OF VANCOUVER, BRITISH COLUMBIA, CANADA.

AUTOMATIC RAILWAY-GATE.

1,308,598.

Specification of Letters Patent.

Patented July 1, 1919.

Application filed April 15, 1918. Serial No. 223,764.

To all whom it may concern:

Be it known that I, ANGELO LATTANZI, a subject of the King of England, and resident of Vancouver, British Columbia, Canada, have invented certain new and useful Improvements in Automatic Railway-Gates, of which the following is a specification.

This invention relates to improvements in railway appliances and it is the principal object of the invention to provide an automatic train operated railway gate which will be moved to closed position as a train approaches the crossing, thus, rendering the temporary blocking or interrupting of traffic positive and preventing collisions.

Another and equally important object of the invention is to provide the gate with novelly constructed and arranged trips 20 which, when engaged by the wheels of rolling stock, will serve to move the gate to opened and closed positions.

The invention consists, furthermore, in the novel arrangements and combinations of the parts of the gate, as well as in the details of the construction of the same, all of which will be more fully described in the following specification and then finally embodied in the clauses of the claim, which 30 are appended to this specification and which form an essential part thereof.

In the drawings:

Figure 1 is a top plan of the improved form of gate and the operating means therefor,

Fig. 2 is a vertical section therethrough,

Fig. 3 is a detail of a portion of the track and the arrangement of the various trips thereon,

Fig. 4 is a fragmentary detail partly in section showing the bracket or rest for receiving the free ends of the gate elements, and

Fig. 5 is a fragmentary detail in perspective of the latch means for certain of the trips.

Having more particular reference to the drawings, in connection with which like reference characters will designate corresponding parts throughout the several views, T represents the usual railway track intersected by a roadway R. Positioned on the roadway R, at points in proximity to one side of the track T are spaced hollow uprights 1 and 2 having their upper ends bifurcated and provided with transversely dis-

posed bolts 3, which as will be noted, serve to pivotally support the usual cross arms 4 and 4^a, the rear ends of which are weighted as at 5 in order that the same will normally 60 assume their "open" or substantially upright positions. It of course will be noted, that the arms 4 are mounted off-center, the longer portions thereof being of lengths sufficient to span the space between the 65 spaced uprights 1 and 2. Brackets 6 are secured to certain of the sides of the uprights 1 and 2 and serve to receive the oppositely disposed free ends of the arms 4, thus affording an effectual stop therefor whereby 70 to limit the downward movement of the same and also effectually bracing the same.

Pulleys indicated by the numerals 7 and 8 are supported in the lower portions of the several hollow uprights 1 and 2 adjacent 75 slots 9 and 10 formed therein, in order that cables, hereinafter described, may be passed thereover.

Spaced gate actuating trips 11 and 12 are pivoted to the sides of one of the rails of 80 the track T as at 13 and have their upper portions formed substantially V-shaped, while the lower portions thereof are bent downward for connection with the arm closing cables 14 and 15 through contractile coil 85 springs 16. As will be noted, these closing cables 14 and 15 are passed over spaced pulleys 17 supported upon suitable brackets arranged in proximity to the roadway and track and are connected with the gate arms 90 4 and 4^a, respectively. Spring arms 18 having certain of their ends bent upwardly as at 19 are positioned adjacent the lower ends of the trips 11 and 12 and are adapted to be engaged therewith subsequently to the depressing of the trips by engagement of the 95 wheels of the rolling stock therewith. In this way, it will be readily understood that the trips 11 and 12 when once depressed will be maintained in such positions until released, by means hereinafter described. Releasing cables 20 and 21 are connected to the 100 arms 4 and 4^a respectively, and extend downwardly through the hollow uprights 1 and 2 over pulleys 8 and about other pulleys 22 105 having connection with the ends of the offset portions 19 of the spring arms 18. Hence, when the trip 11 is depressed by the wheels of the rolling stock passing thereover, the same will act through the closing cable 14 to cause the closing of the arm 4 supported on the upright 1. As the rolling

110

stock proceeds over the track T, the wheels thereof will be engaged with the second or remaining trip 12; depressing the same and causing the tensioning of the spring 16 and 5 the other arm 4^a to be moved to its closed position by means of the cable 15. Simultaneously with the closing of the arm 4^a, the first arm 4 will be permitted to move to its open position, since the arm 4^a will impart 10 a pull to the releasing cable 21; thus disengaging the end portion 19 of the arm 18 from the lower end of the trip 11. Obviously, this operation is reversed when the trip 12 is first depressed.

15 Other trips 23 and 24 are pivotally mounted on the rail of the track T carrying the trips 11 and 12, at points distant therefrom and have their upper portions formed substantially V-shaped while the lower ends are 20 bent downwardly and engaged by short releasing cables 25 and 26, which as will be noted, are extended into engagement with the angular ends 19 of the arms 18. The releasing cables 20 and 26 are extended 25 through a guide 20^a arranged adjacent the trip 12 and the cables 21 and 25 are extended through a guide 21^a arranged adjacent the trip 11. The rolling stock upon proceeding farther over the track T will 30 engage either one of the trips 23 or 24, depressing the same and causing the end 19 of the spring arm 18 connected thereto to be moved out of engagement with its respective end of the trip 11 or 12, thereby releasing 35 said trips and permitting the arms 4 connected thereto to be immediately moved to their upper or open positions.

From the foregoing, it is believed that a full understanding of the construction and 40 operation of my improved gate is afforded. However, in this connection, it is to be noted that the spring 16 serves to prevent the transmission of excessive vibration or abnormal strains to the cables 14 and 15 and 45 to the pivoted arms 4 connected thereto. Further, it is to be also understood that the pulleys 7 and 8 may be of the double sheave

type, if desired, thus rendering the construction more compact.

The various trips 11, 12, 23 and 24 may be 50 arranged on the track T at any desirable distance apart, such as conditions or preference may dictate, providing that sufficient space is afforded to insure proper functioning of the same during the passage of the rolling stock thereover.

Manifestly, the construction shown is capable of considerable modification and such modification as is within the scope of my claims, I consider within the spirit of my 60 invention.

I claim:

1. In combination with a railway track, a gate including spaced pivoted arms, spaced trips pivoted to one side of said track and 65 connected to said arms, spring arms arranged adjacent the track having certain of the ends thereof bent upwardly and adapted for engagement with said trips, said upwardly bent ends of the arms being connected to the oppositely disposed pivoted arms, and other trips pivoted to one side of the track at points distant from said first trips and connected to the upwardly bent ends 70 of the spring arms.

2. In combination with a railway track, a gate including spaced hollow uprights, counterweighted arms pivoted to the upper ends of said uprights, brackets arranged on the uprights for receiving the adjacent ends of 80 the pivoted arms, spaced trips pivoted to one side of said track and connected to said pivoted arms, spring arms arranged adjacent the track having certain of their ends bent upwardly and connected to the oppositely disposed pivoted arms, and other trips pivoted to one side of the track at 85 points distant from said first trips and connected to the upwardly bent ends of the 90 spring arms.

In testimony whereof I affix my signature hereto.

ANGELO LATTANZI.

Copies of this patent may be obtained for five cents each, by addressing the "Commissioner of Patents, Washington, D. C."
